PIPE-THREADING APPARATUS.

1,306,171.

Specification of Letters Patent. Patented June 10, 1919.

Application filed February 14, 1918. Serial No. 217,053.

To all whom it may concern:

Be it known that I, BENJAMIN F. BUTLER, a citizen of the United States of America, residing at Greenfield, Massachusetts, have 5 invented new and useful Improvements in Pipe-THREADING APPARATUS, of which the following is a specification.

This invention relates to improvements in pipe-threading apparatus, and it has for its 10 object to provide a simple, positive, and effective pipe-threading apparatus of the re-cession type, that is, of the type wherein the cutting dies recede from the axis of the pipe as the thread is cut from an end of the 15 pipe toward an intermediate portion thereof, in order to cut what is known as a taper thread. The particular object of the invention is to provide such a pipe-threading apparatus, and one wherein two independently 20 adjustable controls are provided, adapted for preliminary setting, one to predetermine the length of the thread to be cut, and the other to predetermine the depth of the thread to be cut.

25 Heretofore pipe-threading apparatus capable of being preliminarily adjusted for length of thread and depth of thread have been proposed, but have had the serious disadvantage that when preliminary adjustment for length of thread is made, compensating and difficult adjustment must be made for depth of thread, and vice versa.

The present invention, in its essentials, involves the employment of a support for 35 holding a pipe, a support for a means for cutting a thread on the pipe, one of said supports being spirally movable relative to the other, controlling means for then moving the cutting means radially of the pipe 40 to cut a thread of a certain taper on the pipe, means for adjusting the controlling means to permit a thread of a predetermined length to be cut, and means for adjusting the controlling means to cut a thread of any 45 one of several predetermined depths but all of said certain taper; the main feature of the invention being the arrangement whereby either of the two adjusting means may be 50 adjusted independently of the other, and without disturbing the adjustment previously fixed by the other.

The invention is preferably applied to a known type of pipe-threading apparatus in which the cutting dies are permitted to 55 recede as the thread is cut more and more,

by means of the yielding action by levers which are in sliding engagement with abutments or cams on a nut traveling on a hollow screw surrounding the pipe. When the invention is applied to such a structure, a 60 preferable embodiment thereof would include a pipe-cutting device comprising thread-cutting dies spaced around the pipe on an annular support, levers for actuating said dies and pivoted on said support opposite the outer ends of the dies, a hollow externally threaded screw surrounding the pipe and carried by the die-support, a pipe clamping support, a nut rotatable on the pipe-clamping support and 65 on the screw, a slide rod joining the die-support and the nut and having two stops one of which is adjustable, with the support and nut located between the stops, so that the adjustable stop may be set on the 70 rod to predetermine the limits of axial travel of the nut on the screw during a single threading operation, and an annulus adjustable circumferentially of the nut and 75 mounted thereon and carrying a plurality 80 of outwardly radially projecting cams one for coacting with each of said levers. Also, preferably the nut carries a circumferential series of calibrations and the annulus a co-operating index; or vice versa. In short, the 85 invention may be very simply expressed in relation to the known structure just described, by stating that it may be, and is preferably, carried out by splitting up the former nut into two parts, one of which 90 parts remains as the nut and carries the means for engaging the stop rod, and the other part is formed so as to be carried by the first-mentioned part and to be adjustable thereon and carry the lever-controlling abut- 95 ment or cams.

The invention will be more clearly understood from the following description, when taken in connection with the accompanying drawings showing an embodiment of the invention at present preferred.

In these drawings,

Figure 1 is an axial section, taken through the pipe-threading apparatus, with certain of the parts shown in elevation, this view 105 being a section on the line 1-1 of Fig. 2;

Fig. 2 is a section on the line 2-2 of Fig. 1;

Fig. 3 is a fragmentary view showing certain of the parts of Fig. 1 in top plan; and 110

Fig. 4 is a detail view showing certain of the parts in side elevation.

Similar reference characters refer to similar parts throughout the several views of the drawings.

The pipe to be threaded, which in Fig. 1 is shown to be in the course of being threaded, is indicated at 4.

Mounted on a support 5 are a plurality of 10 thread-cutting chasers or dies 6. There are preferably four of these dies, spaced apart 90° as shown in Fig. 3. These dies slide in housings 7 fixed on the support 5. The dies are intended to be held to the work by means 15 of the abutment against their rear ends of the short arms of the levers 8 pivoted to the housings 7. One of these short arms is shown at 8' in Fig. 1. The long arms of these levers have cam surfaces one of which 20 is shown at 8'' in Fig. 1.

The support 5 carries a depending tubular portion 9 surrounding the pipe and externally threaded. This tubular part of the support 5 is screw-threadedly connected, as 25 indicated at 9' in Fig. 1, with what may be termed a nut-structure 10 (see Fig. 1) including a cage 1 provided with clamping means generally indicated at 2 (see Fig. 1) whereby the pipe may be clamped therein 30 and centrally of the tubular part 9 of the die support 5.

The nut-structure 10 includes two removable and separately adjustable annuli 11 and 12. The annulus 11, as shown best from 35 a comparison of Fig. 2 with Fig. 1, is provided with two radial projections 13 bored and counter-bored as indicated at 14. The annulus 12, as will best be seen from a comparison of Fig. 2 with Fig. 1, is provided 40 with four abutments or cams 15, outwardly projecting, spaced apart 90°. Each of these cams 15 is adapted to coat with the cam surfaces 8'' of a lever 8 when the support 5 and the nut-structure 10 are connected by 45 the rods 16. Each rod 16 extends through a bore 14 of a projection 13 and is externally threaded. The thread on each rod 16, as shown clearly in the case of one of the rods in Fig. 1, coats with the thread of a 50 threaded aperture 17 cut through the support 5. As shown in Figs. 1 and 3, the threaded end of each rod 16 has adjustably mounted thereon a lock nut 18. The cam carrying annulus 12 is adjustable circumferentially of the annulus 11 which carries the 55 projections 13, preferably by the aid of a suitable series of calibrations on the annulus 11 and a co-operating index 19 on the annulus 12, as shown in Fig. 4; and when the 60 parts are thus adjusted as desired, the annulus 12 may be locked to the annulus 11 by means of the thumb screw 20 shown in Fig. 2. In order that the annuli 11 and 12 may be readily removed, these parts are held in 65 place on the nut structure 10 by means of

an internally threaded ring 21, screwed on an upwardly extending reduced portion 22 of the nut-structure 10.

Before describing the operation of the device during the thread-cutting operation, 70 pursuant to any selected adjustment, it should be explained that by circumferentially adjusting the annulus 12 on the annulus 11 the long arm of the levers 8 will be more or less held out from the axis of 75 the pipe, according to the positions of the cams 15 relative to such levers, at the commencement of the thread-cutting operation, so that the cutting of the first part of the thread will be of greater or less depth. 80 Thereafter, due to the design of the cam surfaces 8'', the levers 8, coating with the selected points on the cams 15 will, as the cams and the axes of the levers come closer together, permit the dies to recede as the 85 cutting of the thread is proceeded with, whereby the thread will have the required taper. It should also be explained, preliminarily, that the function of the rods 16 is to limit the amount of travel of the cams 15 90 away from the axes of the levers 8 before any pipe-threading operation, thereby to limit the length of the permissible thread. This adjustment is obtained by means of the nut 18, which acts as a lock nut after the 95 threaded part of the rod 16 has been properly adjusted relative to the threaded bore 17 of the support 5. Thus the apparatus shown in Fig. 1 has been set so that at the commencement of the threading operation shown, the head or fixed stop 23 on the rod 16 of Fig. 1 was in the counter-bored part of the aperture 14; the completion of the thread of course occurring when the cams 15 reach the limit of their possible 100 movement toward the axes of the levers 8.

Operation:

First, as just described in the second preceding paragraph, the rods 16 are adjusted relative to the support 5 and the lock nuts 18 tightened to lock the rods in the selected adjustment, to preliminarily set the threading apparatus for the cutting of a thread of a predetermined length, and the annulus 12 is adjusted circumferentially of the annulus 11 to set the cams 15 so that a certain point on the curved outer surface of each cam is contacted with the cam surface 8'' of the coating lever 8, to preliminarily adjust the apparatus for the cutting of a thread of a 110 predetermined depth. To make this last adjustment, the calibrations and index shown in Fig. 4 may conveniently be utilized. Finally, the thumb screw 20 of Fig. 2 is tightened. The pipe 4 to be threaded 115 is inserted into the nut-structure 10 and clamped within the cage 1 by means of the clamping agent 2. Then the member or support 5, which carries the dies 6, is rotated by means of the handles or spokes 25, 120 125 130

- inserted in the sockets 5' carried by the member 5. The member 5 is thereby rotated and spirally advanced relative to the nut-structure 10 and the pipe 4 clamped 5 therein, the tubular portion 9 of the support 5 screwing down into the cage 1 of the nut-structure 10. This rotating and advancing movement of the member 5, at the same time rotates the annuli 11 and 12 on 10 the nut-structure 10, by means of the rods 16, these rods serving to hold the member 5 and the annuli 11 and 12 to common quantitative rotation. Thereby the selected point on the curved outer surface of each 15 cam 15 remains in contacting relation with the cam surface 8'' of its coacting lever 8. The rods 16, however, being smaller in diameter than the apertures 14, do not interfere with the descent of the axes of the 20 levers 8 toward the cams 15, and as a result, as the cutting of the thread progresses, the cams 15 come closer and closer to the axes of the levers 8 and thereby permit the recession of the dies 6 away from the axis of 25 the pipe to cut the selected taper thread. The parts abut and prevent further descent of the axes of the levers 8 toward the cams 15 at the instant when the thread is completed to the predetermined length.
- 30 The devices whereby the threaded connection 9' is provided between the tubular part 9 of the support 5 and the nut-structure 10 form no part of the present invention, and therefore have not been previously described, as they have been used heretofore and are believed to be well-known in the art. A brief description of such devices, however, may advantageously be set forth at this point. It will be noted from Fig. 2 35 that the nut-structure 10, just below the annular seat 10' (Fig. 1) for the annulus 11, is hollowed out, as indicated at 27, Figs. 1 and 2. At diametrically opposite points, as indicated in broken lines in Fig. 2, the wall 45 10'' of the nut-structure 10 is transversely slotted to accommodate radially slidable threaded segments 28. One of these segments 28 is shown clearly in cross section in full lines in Fig. 1. As shown, each segment 50 28 is recessed in its outer face for the reception of a pin-held leaf spring 29, tending to hold the segment retracted so that its threaded inner face is out of engagement with the external threads of the tubular 55 part 9 of the support 5. Slidably mounted on the annular surface 10'' (see Fig. 1) of the nut-structure 10, is an annulus 30 carrying two cams 31, each adapted, when the annulus 30 is turned on the nut-structure 10 60 and relative to the annuli 11 and 12, to force one of the segments 28 against the tendency of the spring 29 of such segment, into threaded engagement with the tubular part 9 of the support 5. The parts are so arranged that the annulus 30 may be easily 65 turned in one direction, to permit the segments 28 to withdraw from threaded engagement with the tubular part 9 of the support 5, or in the opposite direction, to force the segments 28 into threaded engagement with said part 9; irrespective of the adjustment of the annulus 12 on the annulus 11, or of the relative positions of the cams 15 and the axes of the levers 8. The annulus 30 is provided with a plurality of 70 depending handle-extensions 30' as shown in Figs. 1 and 2. The presence of the parts just described permits, after the completion of a threading operation on one pipe, the parts to be reset with the head 23 of each 75 rod 16 seated in the counter-bored part of the aperture 14, in readiness for the cutting of a thread on a second pipe. Of course the annulus 30 is turned to release the segments 28 from the tubular part 9 of the support 80 5 to reset the apparatus for a second threading operation, and the annulus 30 is moved in the opposite direction to reengage the segments 28 with the said part 9 just before the commencement of the second threading 85 operation.
- I claim:
1. In pipe threading apparatus, the combination comprising a work holder, a die head in screw-threaded engagement therewith, die actuating levers mounted on said head, a member mounted on said work holder rotatable with said head and restricted against axial movement on the holder and a cam plate mounted on said member 95 in actuating engagement with said levers.
  2. In pipe threading apparatus, the combination comprising a work holder, a die head in screw-threaded engagement therewith, die actuating levers mounted on said head, a member mounted on said work holder rotatable with said head and restricted against axial movement on the holder, a cam plate mounted on said member in actuating engagement with said levers provided 100 with cam surfaces for setting the levers in initial position for the desired depth of cut.
  3. In pipe threading apparatus, the combination comprising a work holder, a die head in screw-threaded engagement therewith, die actuating levers mounted on said head, a cam member rotatably mounted on said work holder and restricted against axial movement thereon and having its cam surfaces in actuating engagement with said 105 levers, driving pins slidably interconnecting said cam member and the die head to cause these members to rotate together while permitting relative axial movement, and adjustable means on said pins for limiting the 110 movement of the head from the cam member.
  4. In pipe threading apparatus, the combination comprising a work holder, a die head in screw-threaded engagement there- 115

with, die actuating levers mounted on said head, a member rotatably mounted on said work holder and restricted against axial movement thereon, an adjustable stop connection between said member and head for predetermining the length of thread, and a cam plate mounted on said member in actuating engagement with said levers.

5. In pipe threading apparatus, the combination comprising a work holder, a die head in screw-threaded engagement therewith, die actuating levers mounted on said head, a member rotatably mounted on said work holder and restricted against axial movement thereon, an adjustable stop connection between said member and head for predetermining the length of thread, and a cam plate mounted on and circumferentially adjustable on said member in actuating engagement with said levers.

6. In pipe threading apparatus, the combination comprising thread-cutting dies, levers for actuating said dies, a support on which said dies are movably mounted and 25 on which said levers are pivoted, a screw carried by said support, a second support adapted to be clamped to the pipe, a nut on the second support engaging the said screw, a

stop motion connection between the first support and the nut structure adjustable to 30 predetermine the limits of axial travel of the first support with respect to the second, and a member adjustably mounted on the nut and carrying a cam for coacting with one of said levers.

7. In pipe threading apparatus, the combination comprising thread-cutting dies, levers for actuating said dies, a support on which said dies are movably mounted and on which said levers are pivoted, a screw 40 carried by said support, a second support adapted to be clamped to the pipe, a nut on the second support engaging the said screw, a stop motion connection between the first support and the nut structure adjustable to 45 predetermine the limits of axial travel of the first support with respect to the second, and an annulus adjustable circumferentially of the nut and carrying a plurality of outwardly radially projecting 50 cams one for coacting with each of said levers.

In testimony whereof I have signed my name to this specification.

BENJAMIN F. BUTLER.
